UNITED STATES PATENT OFFICE.

MANUEL BRETOS Y CLAVERIA, OF SANTIAGO DE CUBA, CUBA.

FOLDING DOOR.

Application filed October 15, 1923. Serial No. 668,755.

To all whom it may concern:

Be it known that I, MANUEL BRETOS Y CLAVERIA, subject of the King of Spain, residing at Gallo 22, Santiago de Cuba, 5 Oriente, have invented certain new and useful Improvements in Folding Doors, of which the following is a specification.

This invention relates to metallic folding doors, and has as its principal object, the 10 provision of an improvement to such doors, whereby the door can constitute an awning, which, being of metal, lasts indefinitely, and at the same time can be easily folded.

Other and further advantages of the invention will be brought out in the course 15 of the specification and with the aid of the attached drawing, in which the same reference characters designate the same parts, and wherein,

20 Figure 1 is a front elevation showing the raised front of a door provided with the improvements which are the object of the present invention;

Figure 2 is a vertical section on line 2—2 25 of Figure 1;

Figure 3 is a similar section showing the door in folded position;

Figure 4 is a section on line 4—4 of Figure 2;

30 Figure 5 is a partial section on line 5—5 of Fig. 2;

Figure 6 is a detailed view of the side elements.

In said figures of the drawing is shown 35 a folding door 1 of an ordinary type, whose side rail guides 2 present, at the upper part, extensions or integral branches 3 directed forwardly and slightly downwardly, and also extensions 4, from the branches 3 directed downwardly. These have the object 40 of diverting the door 1 from its normal path between the guides 2, and directing it between the branches 3 so as to act as an awning, as will be more fully explained. 45 The door can also be directed between the extensions 4 when it is desired to cover a space in front of the doorway occupied by a glass-case, counter, etc.

In line with the branches 3, are placed 50 two guides 5, made of angle irons and fastened at their backs to brackets 6, pivoted at 7 to a plate 8 secured by screws 9 to either side of the doorway and projecting beyond the same. The lower flanges of the

rear ends of the guides 5, are positioned as 55 extensions, as shown at 6', below the lower wings of the branches 3 which act as stops for guides 5.

Between the inclined guides formed by 60 the brackets or branches 3 and pivoted arms 5, the door 1 can run until the lower border 1' of the door is stopped by an angular plate header 10, secured between the free 65 ends of the guides 5 and having its larger flange depending.

On each side of the guides 5, externally 70 thereof, and along their entire lengths, plates 11 are secured so as to project downward beyond the guides 5, to receive on the interior faces of its projecting portion, 75 a number of narrow vertical plates 12, pivoted at their upper ends, at 13, to the plates 11, and hanging to form awning sides with contacting borders, folded or corded as shown at 12' in Figs. 5 and 6, except at the top ends, which top ends present bevels 12 to permit free movement of the parts.

To the inner face of the depending flange 80 part of the plate or header 10, is joined the rolled top border of a hanging plate 15, which plate constitutes the front part of the awning.

Secured to the top wing of the plate 10 is a bolt-eye 16 to which is secured one end 85 of a cable 17 which passes under a pulley 18 loosely mounted on a bracket-arm 19 secured to the middle part of the doorway, which cable is guided by pulleys 19, 20 and 21 in the arrangement as shown in Figure 2, or any other convenient one, for placing 90 the free end of the cable 17 within reach of an operator's hand.

By the following, the operation of the device will be clear:

Assuming the parts to be in the position 95 shown in Figs. 1 and 2, that is, with the folding door 1 moved down between the guides 3 and 5, it will be sufficient to fold the awning, to pull on the cable 17, the door 1 having been run out of the guides 100 3 and 5. This rotates the guides 5 around their hinges 7, and upwards into the position shown in Fig. 3, where it is clearly shown how the pivoted plate 15 and the pivoted awning sides 12, fold compactly together.

On moving the awning downwardly, all 105 the parts return to the proper position by

gravity and it is only necessary to slide the door 1 down between the guides 3 and 5 for the operation to be complete.

Having now described my invention, and 5 one form in which the same is realized, what I desire to protect by Letters Patent is,

1. In a folding door, a sliding door, a vertical guide frame for the door, and a folding, forwardly projecting guide frame, 10 connected to the vertical guide frame, whereby to receive the door and form an awning.

2. A device according to claim 1, depending, overlapping plates connected to the said projecting guide and forming awning 15 sides, a depending plate hinged across the ends of the projecting guide and forming the awning front, and means for raising the projecting guide, the depending over-

lapping plates, and the depending plate, when the sliding door is removed from the 20 projecting guide.

3. In a folding door, a door frame, brackets fixed to the frame, grooved door guides fixed to the brackets, forwardly projecting guide portions on the door guides, 25 a header connected across the ends of the forwardly projecting guide portions, narrow, depending, plates attached to the projecting portions, a depending plate connected to the header, and a pivot connection between the projecting portions and the grooved door guides. 30

In testimony whereof I have signed my name to this specification.

MANUEL BRETOS y CLAVERIA.
